DETACHABLE BUTTON

John L. Friedrich and Frank P. Stockdale, Los Angeles, Calif.

Application February 6, 1934, Serial No. 709,964
Renewed October 3, 1936

2 Claims. (Cl. 24—108)

Our invention has reference to buttons for wearing apparel, and it relates particularly to cloth covered buttons as used on wash dresses which consist of metal bodies having their tops covered with cloth and their bottoms each formed with an opening from which cloth is protruded to permit sewing of the button to the dress. At present it is the practice of wash dress manufacturers to sew the cloth buttons on by hand, there being no machines for this purpose.

This hand sewing of cloth covered buttons to relatively inexpensive wash dresses is a very costly part of the manufacturing expense. Also, in laundering a wash dress with the buttons attached, the resultant rust from the metal parts of the button discolors both the cloth of the button and the dress.

It is a purpose of our invention to provide a two part button cloth covered or otherwise, in which the parts are separable, and wherein one part can be rapidly sewed to a dress by the conventional machines provided for the purpose, while the other part which is cloth covered, can be manually attached to the first part and securely held thereon by coacting fastening means on the two parts, to prevent accidental removal or detachment of the button from the dress, and yet permit intentional manual detachment thereof when it is desired to wash the dress separately from the buttons. Thus, in accordance with our invention the hand sewing of the buttons to a dress as well as the attendant expense thereof is eliminated, and the button, although securely attached to the dress is readily removable to permit washing and ironing of the dress without the cloth covered part of the button thereon, and thereby preventing discoloration of the dress material from rust and facilitating ironing of the dress by reason of the absence of the buttons.

It is also a purpose of our invention to provide a button having head and socket elements of angular construction as distinguished from the round construction of the head and socket elements of the conventional separable fastener, whereby the head element is fixed against rotation in the socket element, and the angular faces and corners of the two elements presented by reason of their angular construction, prevent rotation of the head element in the socket element, and permit separation of the two elements only when either element is subjected to a direct axial pull.

We will describe only one form of button embodying our invention and will then point out the novel features thereof in claims.

In the accompanying drawing:

Fig. 1 is a view showing in side elevation and partly in section one form of button embodying our invention in applied position on a piece of fabric which represents part of a dress.

Fig. 2 is an enlarged view partly in section showing in bottom plan the socket part of our button.

Fig. 3 is a transverse sectional view taken on the line 3—3 of Fig. 2.

Fig. 4 is an enlarged bottom plan view of the head part of the button.

Fig. 5 is an enlarged sectional view taken on the line 5—5 of Fig. 1.

Our invention in its present embodiment comprises a button having a head part and a socket part designated generally at A and B, respectively. The head part constitutes the ornamental part of the button and includes a top 15 and rim 16 both of which are covered with cloth as shown in Fig. 1, and a metal back 17. The metal of which the back is formed is outstruck at its center to form a head fastening element 18 having a neck 19 of reduced cross section. The element 18 is of angular form in cross section to provide a plurality of faces 18^a angularly disposed to provide intervening corners 18^b. In the present instance, the element 18 is square to provide four such faces 18^a and corners 18^b, but it will be understood that the head element can be made of any angular form. Also, the head element is slightly tapered from the neck 19 to its free end in order to facilitate introduction of the head element into the socket element.

The socket part B of the button comprises a flat metal body 20 of substantially square form in outline to conform to the contour of the conventional type of socket element which is capable of being sewed to a garment by the well known machines provided for the purpose. Openings 21 in the body 20 are provided to receive the threads for sewing the socket part to the fabric 22 of the wash dress or other form of garment, as illustrated in Fig. 1.

As best shown in Fig. 3, the socket body 20 is flanged at its edges and inturned to form a continuous lip 23 which is provided for the purpose of securing a retaining spring 24 in proper position on the body. The body 20 is outstruck at its center to form a socket fastening element 25 on a neck 26, the latter having slots 27 to receive portions 24^a of the spring 24. The element 25 is

of the same shape as the head element 18, but of a size to snugly receive the latter and so that its inside angular faces 25^a and corners 25^b have uniform contact with the corresponding faces 5 and corners of the head element.

In practise, the socket part B is secured to the fabric 22 so that the open end of the socket element 25 is presented to the outside of the dress of which the fabric is a part. Thus to attach 10 the button to the fabric it is necessary only to center the head part on the socket part when the head element 18 can be forced past the spring portions 24^a and into the socket element 25. In the fully seated position of the head element 18 15 the spring portions have sprung back so as to repose within the slots 27 to grip the neck 19 and thus secure the head element within the socket. In this manner the button is detachably secured to the fabric.

20 With the parts of the button assembled as described, the angular faces and corners of the two elements are now in snug contact so that they coact to secure the elements against rotation relatively. This prevents rotation of the button 25 on the garment, the resultant wear of the contacting surfaces, and the possible detachment of the button head from the garment by reason of such rotation. But what is more important is that this angular construction of head and socket 30 elements presents coacting surfaces or walls that function as abutments to secure the head element against withdrawal from the socket element except by a direct axial pull on the button sufficient to overcome the tension of the spring portions 24^a.

35 Thus the button is securely retained on the garment against accidental detachment under the stresses to which the head element is subjected in the normal wear of the garment.

It will be noted that the end of the head element 40 and the bottom of the socket element are flat to have uniform contact one with the other, and thus other walls are provided which coact with the side walls of the elements to secure the two against separation under the normal stresses

to which the button head is subjected when on the garment.

Although we have herein shown and described only one form of button embodying our invention, it is to be understood that various changes and modifications may be made herein without departing from the spirit of our invention and the spirit and scope of the appended claims. 5

We claim:

1. A button comprising; a head part having a 10 substantially flat body and a head formed centrally of and projecting laterally from said body and of angular form circumferentially, a reduced neck connecting said head to said body; a socket 15 part having a substantially flat body and a socket formed centrally of and projecting laterally from said body and of angular shape interiorly to snugly receive said head and coact therewith in forming a plurality of circumferentially spaced abutments which cooperate to secure the head 20 and socket against rotation relatively; and a spring secured within the body of said socket part and having portions extending into said socket to engage said head.

2. A button comprising; a head part having a 25 substantially flat body and a head formed centrally of and projecting laterally from said body and of angular form circumferentially, a reduced neck connecting said head to said body; a socket 30 part having a substantially flat body and a socket formed centrally of and projecting laterally from said body and of angular shape interiorly to snugly receive said head and coact therewith in forming a plurality of circumferentially spaced abutments which cooperate to secure the head and 35 socket against rotation relatively, said head being exteriorly tapered toward its free end and said socket being interiorly tapered toward its inner end to receive said head; and a spring secured within the body of said socket part and having 40 portions extending into said socket to engage said head.

JOHN L. FRIEDRICH,
FRANK P. STOCKDALE.
